UNITED STATES PATENT OFFICE.

JEAN VAN DE PUTTE, OF ASSCHE, NEAR BRUSSELS, BELGIUM.

TRACK CLEARER FOR VEHICLES.

Application filed December 20, 1927, Serial No. 241,425, and in Belgium December 24, 1926.

The present invention relates to a track-clearer for vehicles constructed to sweep sideways any impediment to be met by the progressing vehicle.

5 The device will be mainly constructed by means of a frame member projecting in front of the vehicle and presenting two supporting branches, each inclined from a head upon the longitudinal axial plane of the vehicle. A 10 disc freely rotating about a vertical axis is provided at the apex of the angle of the branches and a series of discs are supported by each of said branches, said discs being capable of rotating freely in one direction 15 only, namely in the direction ahead sideways, so that any movable impediment coming in contact with the track-clearer will be shifted sideways along a moving edge formed by the rotary bodies, all the discs overlapping each 20 other in succession over a certain distance. Practically the branches referred to will be formed by means of straight channel-irons, meeting at an angle at the apex of which will be mounted a freely rotating disc, where- 25 as each branch will be fitted with a succession of discs mounted about substantially vertical axes and capable of rotating in one direction only, namely from ahead sideways. To constitute a perfectly acting movable railing 30 in front of the vehicle, the discs or wheels to be used preferably will advantageously overlap each other.

The invention will find its preferred application in motor-cars to be used by police 35 forces, for instance in dispersing crowds, and in this application the track-clearer will comprise preferably an upper frame member, removably adapted to the car body on a level with the upper part of the motor-bonnet, whereas a lower frame will be adapted to the chassis frame, the latter member being provided with means allowing the adjustment of same with relation to the ground. A motor-car fitted in this way will sweep the track 45 without hurting living beings, either standing up or stretched out on the ground.

In order that the invention may be clearly understood, it will be described in its preferred form of embodiment, with reference 50 to the accompanying drawings.

Fig. 1 is a vertical side-elevation of the front part of a motor-car equipped with the double track-clearer, whereas

55 Fig. 2 represents half a plan view upon the motor-hood and half a plan view upon the chassis-frame of the car.

The two frames 1, formed by means of channel-irons of appropriate size and section, are adapted the one in removable manner to the car-body, coming on a level with the upper part of the motor-bonnet, whereas the lower one is adjustably adapted to the chassis-frame of the car, such as for instance about a pivot 4 forming part of the main frame irons. Said frames are formed with two front 60 branches 6 meeting at an angle 7 in front and approximately in the vertical longitudinal axial plane of the vehicle. At the apex of the angle 7 will be mounted a disc 2 freely rotating about a vertical axis. Upon each of the 65 branches 6 are mounted a series of similar discs 3, the discs 2 and 3 overlapping each other in succession for a certain distance. The discs 3 can rotate in the direction of the arrows illustrated, namely the direction ahead 70 sideways. Any movable impediment coming in contact with the discs 2 will impart to said discs a rotation in one or the other direction, and said impediment will be shifted thereby rolling eventually along the laterally 75 disposed discs 3 forming a moving railing, sweeping the object laterally out of the track of the vehicle.

This sweeping motion is also facilitated by the direction of free rotation of the discs 3. A 80 living being struck in said conditions will be cleared without being thrown down or wounded and the violence of the sweeping movement will remain proportional to the speed of the vehicle. It is obvious that the 85 lower track-clearing element acts in the same conditions for impediments stretched out upon the ground, so as to bring them out of the track of the wheels of the car.

The upper frame member can be mounted 90 removably by means of bolts to the car body, whereas the lower element pivotally mounted to the chassis-frame at 4 can be adjusted with relation to the ground, as for instance by means of a screw 5 acting on a nut forming 95 part of the free end of frame 1, said screw being driven by a crank and bevel gear.

Mounting and replacing the track-clearers can be operated in a minimum of time and it will really constitute a practical safe-guard 100 for human beings.

It is obvious that the discs 3 can be replaced by cylindrical bodies acting in the same way, said cylindrical bodies requiring preferably a different mounting and frame.

Practically the frames 1 will occupy a horizontal position and the apexes of the angles

will advantageously fall in a common vertical line. However, numerous constructional modifications are possible without departing from the scope of the present invention.

5. I claim:

1. A track-clearer for vehicles, comprising a frame member projecting in front of the vehicle and formed with two branches meeting at an angle ahead; a disc freely rotating about a vertical axis at the apex of the angle, a series of discs supported by each of said branches upon substantially vertical axes, said discs being capable of rotating freely in one direction only, namely in the direction ahead sideways, all the discs overlapping each other in succession over a certain distance, substantially as described.

15. 2. In a motor-car a track-clearer compris-

ing an upper frame member removably adapted to the car body, a lower frame member adjustably adapted to the chassis frame, said members projecting in front of the vehicle and formed each with two branches meeting at an angle ahead, a disc freely rotating about a vertical axis at the apex of each angle, a series of discs supported by each of said branches upon substantially vertical axes, said discs being capable of rotating freely in the direction ahead sideways, the discs overlapping each other in succession for each frame, and means for adjusting the position of the lower frame member with relation to the ground.

20. In testimony whereof I signed hereunto my name.

JEAN VAN DE PUTTE.
